FRAMELESS WINDOW SCREENS

Charles Raymond Parrish, West Columbia, S. C., assignor to Loxscreen Company, Inc., Columbia, S. C., a corporation of Georgia

Application August 5, 1952, Serial No. 302,770

7 Claims. (Cl. 160—328)

This invention relates to screens and particularly to window screens of the frameless or collapsible type.

In recent years the frameless screen, made as a rule of flexible screening attached at top and bottom to rigid rails, but otherwise frameless, has come into widespread use because of its easy application and storage. In mounting such a screen, it is customary to attach its rigid top and bottom rails to the corresponding parts of a window frame and depend on tensioning of the screening to hold its edges tight or flush against the sides of the frame. To obtain such tensioning resort has been had to adjustable connections between one or both rails of the screen and the window frame, sometimes coupled with spring pressure.

The main difficulty with the adjustable connections heretofore employed on such screens is that they have required adjustment each time the screen is closed to provide what seems to be the proper tautness. Consequently, depending on the operator, the screens may either be undertensioned, leaving openings along their sides for entry of insects, or overtensioned and it is practically impossible to obtain the correct tension every time the screen is used. While undertensioning has a temporary disadvantage, overtensioning is the more objectionable since it may permanently damage the screen by stretching the screening beyond its limits or even pulling it from the rails.

It is therefore the primary object of the present invention to provide an improved frameless screen which, while of adjustable tension, is so connected to a window frame that the tension, once adjusted, is automatically obtained each time the screen is closed.

Another object of the invention is to provide an improved frameless screen connectable at a preselected tension to a window frame in which the tension adjusting element may be mounted on either the screen or the window frame.

An additional object of the invention is to provide an improved frameless window screen wherein a connection to a window frame incorporating spring means for reducing the strain on the screen, is enabled to be adjusted to preset the tension of the screen at each closing.

A further object of the invention is to provide an improved frameless window screen having a connection between screening and bounding rails which in conjunction with an adjustable connection for predetermining tension of the screen, minimizes possible damage on closing.

Another object of the invention is to provide an improved frameless window screen which is of rugged construction, readily installed and operated, effectively closes the window opening to insects, from indoors, and has an exceptionally long life.

Other objects and advantages of the invention will appear hereinafter in the detailed description, be par-

2

ticularly pointed out in the detailed description, and be illustrated in the accompanying drawings, in which:

Figure 1 is a fragmentary front elevational view of a preferred form of the window screen of the present invention, showing it installed in a window opening.

Figure 2 is a vertical sectional view taken along the lines 2—2 of Figure 1.

Figure 3 is a horizontal sectional view taken along the lines 3—3 of Figure 1.

10 Figure 4 is a fragmentary horizontal sectional view on an enlarged scale, taken along the lines 4—4 of Figure 1.

Figure 5 is a fragmentary front elevational view of a modified form of screen and adjustable connection.

15 Figure 6 is a rear elevational view of the device of Figure 5.

Figure 7 is a side elevational view of the device of Figure 5.

20 Figure 8 is a fragmentary front elevational view of a third form of screen and mounting; and

Figure 9 is a side elevational view of the screen of Figure 8.

25 Referring now in detail to the drawings in which like reference characters designate like parts, the improved frameless, collapsible or rollable screen of the present invention is comprised of flexible screening 1 of wire, plastic or other mesh of suitable size to keep out flies, mosquitoes or other insects. This screening is bounded and attached or fixed at top and bottom to rigid top and bottom rails, cross-members or stiffeners, 2 and 3, respectively. For attaching the screening to wooden rails such as employed in the embodiment of Figure 1, the rails may be grooved in their front faces to provide spaced parallel grooves 4 adjacent the contiguous edges of the rails into which the upper and lower ends of the screening are pressed. This screening may be locked in the grooves 4 by splines or rods 5 of metal or plastic, depending on the material of which the screening is made. These splines are preferably of single thickness intermediate their ends and doubled over at either end to give added strength to the free marginal edges of the screening. As desired, the splines 5 may be wedged or held, as by nails 6, in the grooves 4.

30 40 45 While applicable to other types of windows, the screen of the present invention, for illustrative purposes, has been applied to a wooden frame 7 of a conventional double-hung window. In such application, the screen is preferably hung outside the window sash (not shown) and suspended or hung from the upper outer sash, guide or bead molding 8. The screen may be simply and effectively hung from the upper molding 8 by a pair of angle brackets or hangers 9, each secured, as by screwing, to the underface of the molding toward one end 50 55 thereof and each disposed so that its vertical or depending leg 10 is flush, exteriorly, with the outer face of the molding. In each of the depending legs 10 is an aperture or opening 11 for receiving the hooked or downwardly bent end 12 of a hook 13 screwed into the inner face of the upper rail 2 above its groove 4. It will be noted from Figure 2 that the corner of the upper rail between the upper molding 8 and the header 14 of the frame 7 is rounded, beveled or cut-back. This construction ensures that the rail, when fulcrumed about its 60 65 70 75 80 85 hooks 13 on tensioning of the screen, will engage both molding and header, thus providing a double seal at the top of the screen.

Once the screen is hung from the brackets 9, it is drawn taut to seal the top and sides of the window opening, the top in the manner just described and the sides by engagement of the unreinforced edges or sides 15 of the screening 1 with the outer faces of the outer side

moldings or sash guides 16. Such tautening or tensioning is here obtained by an adjustable tensioning device anchored to the window sill 17. One or more devices may be used, depending on the size of the screen, but two will normally suffice, one substantially aligned vertically with each of the brackets 9. The tensioning device is a principal feature of this invention and three forms of it are illustrated in the accompanying drawings, one in each of Figures 1, 5 and 8.

Referring first to the embodiment of Figure 1, the tensioning device there shown, designated generally as 18, is comprised of an anchor, catch, connecting or securing member or element in the form of an eye or T screw 19, T-headed by a transverse elongation of its eye 20. This anchor screw 19 is screwed vertically into the sill 17, with its eye or T-head 20 adjustably spaced thereabove a distance determined by the number of turns taken on the screw.

The screen is latched or locked to each of the anchor screws by a latch or latching or locking member 21, carried by the lower rail 3 and mounted on or secured to its inner face. Forming the body portion or body 22 of the latch is a base plate disposed vertically, transversely of the rail, and secured, adjacent its upper end, to the rail, as by a screw 23. The body 22 terminates at its upper end in an integral flange, lip or detent 24 which projects substantially horizontally inwardly from the rail, normal to the body. This detent is round or tapered-nose and necked intermediate its ends to provide a notch 25 on either side for receiving or seating the legs 26 of a U-shaped spring wire lever, clip or clamp 27.

The lever 27 is designed to serve as the actuating and locking element of the tensioning device. To this end, its arms or legs 26 are spread adjacent its closed upper end 28 to form a handle within which is included an elongated opening 29 of sufficient area to encompass or slip over the head 20 of the anchor screw 19. Straight over the area of the detent 24, the legs 26 are again outwardly adjacent their lower or open ends for journaling or pivotally attaching the lever 27 to the body 22 through a pair of ears, or wings 30, apertured for this purpose.

Integral with and projecting inwardly from a lower portion of the body, the ears 30 are vertically disposed and spaced from each other horizontally sufficiently to straddle or receive therebetween the shank 31 of the anchor screw 19 but not its head 20. Instead, the head 20 is designed to slide or ride on and be cammed by the upper edges 32 of the ears, the edges or cam surfaces or shoulders 26 for this reason preferably being arcuately convex and curving downwardly beyond the apertures 33 in which the lever 27 pivots.

To operate the tensioning device, the head 20 of the anchor screw is slipped through the opening 29 in the handle 28 of the lever 27. The lower rail 3 of the screw is then pulled in by the handle until the head 20 reaches the cam surfaces 32 of the ears 30, to which it is guided between the legs 26. The lever is then swung up to engage the inner face of the head and force the latter to ride up the cam surfaces. Toward the upper limit of the swing of the lever to substantially vertical position, its legs 26 are sprung to pass over the outer end of the detent 24, finally springing into the notches 25 to lock the screen in place.

Adjustment of the tension of the screen will usually be necessary when the screen is first mounted. This is then readily accomplished by turning the anchor screw 19 in or out until it is at the proper position perpendicularly of or normal to the sill to provide the desired tension when the screen is locked in place. Thereafter, no further adjustment will normally be necessary and the screen will be placed under the same correct tension each time it is closed by snapping the lever 27 over the anchor screw 19 to locked position.

It will be noted that considerable clearance has been 75

left between the lower rail 3 and the window sill 17. Such clearance is required to afford a sufficient range of adjustment of the tensioning device but leaves an opening below the rail which must be closed. This is readily accomplished by a sealing plate 34, preferably in the form of an angle iron, the upper or upstanding leg 35 of which is floatingly clamped between the inner face of the lower rail 3 and the inwardly offset lower portion of the body 22 of the latching member 21, the body preferably being made of resilient material for this purpose. The lower or horizontally directed leg 36 of the plate is designed to rest on the sill 17. The plate thus provides simple means for sealing the lower edge of the window opening for any adjustment of the tensioning device.

While shown applied to a screen having a metal lower rail 37 to which the screening 1 is clamped through a bar 38 held in a doubled-back upper end portion 39 of the rail, the tensioning device of the embodiment of Figures 5-7 is in most respects the same as that of the first embodiment. Thus, it also utilizes a T-headed anchor screw 38 for adjustment of tension but with an X-bar head 39 instead of an eye. And, as in the first embodiment, the latching member includes the same spring lever 27, pivoted between camming ears 30, and is secured to the lower rail 3. The difference is primarily in the upper part of the latching member. Here, the body portion or base plate 40, made also of a strip of spring metal or like resilient material, is looped or doubled inwardly between the ears 30 and securing bolt 41 to form a transverse expansion loop 42. This enables the base plate 40 to elongate or expand longitudinally under tension. It thus provides a yieldable or resilient connection between the screen and the sill 17, which reduces the stresses on the screening without affecting the presetability or predetermined adjustability of the tension applied to the screen on closing. The loop 42 also renders a separate detent unnecessary, a rounded nose 43 and vertically aligned notches 44 in either side serving to receive and seat the legs 26 of the lever 27 and hold the latter in locked position. If desired, a prong 45 may be formed at the upper end of the base plate 40, which may be driven or slid into the lower rail 3 to reduce the shear stresses on the bolt 41.

The embodiment of Figures 8 and 9, anchors the screening 1 in wooden rails 2 and 3, as in the first embodiment, and its tensioning device also applies preset or predetermined tension or tautness to the screen. However, the structural details of the tensioning device are considerably different. This device is comprised essentially of a catch member or bracket 46 secured to the window sill 17 and a latch member carried by the lower rail 3 and having a spring lever 47 engageable and interlockable with the catch member, with an adjusting element 48 for varying the unlocked, free or untensioned vertical spacing between the latch and catch and thus adjusting their relative positions perpendicularly of the sill.

The latch bracket 46 is preferably a one piece stamping, having a base 49, screwed or otherwise secured to the sill 17. Upstanding centrally from the outer edge of the base is a central tongue 50 designed primarily to floatingly clamp the sealing plate 34 to the lower rail 3. At the sides of the tongue 50 and spaced inwardly therefrom relative to the sill 17 are a pair of spaced upstanding fingers or catch elements 51 having their upper portions curved or bent downwardly and inwardly to form hooks by the concave shoulders 52.

The latch member of the tensioning device is carried on the lower rail 3 and is attached to the inner face thereof by an eye screw 53. Horizontally disposed, the eye 54 of the screw 53 serves as a platform or seat for an adjusting nut 55 which threadedly engages the stem 56 of an eye bolt 57. The eye 58 of this bolt in turn supports a lever or clamp 59 for engaging and inter-

locking with the hooks 52 of the catch or anchor bracket. The lever 47, formed of a spring or wire rod, has a substantially central saddle or reverse bend 59, for interfitting with and positioning the lever longitudinally relative to the eye 58 of the supporting bolt 57. On either side of the saddle the lever branches or spreads outwardly as a pair of outspread arms or wings 60. These arms are preferably axially aligned adjacent the saddle and upturned toward their outer ends, one of the arms terminating in a loop 61 forming the handle of the lever.

In locking the tensioning device of this last embodiment, the lever 59 is grasped by its handle 62 and the far arm 60 is swung into the corresponding hook 52 of the catch 46. Using this hook as a fulcrum, the other arm of the lever is then pressed or forced under the other of the hooks 52, thereby locking the screen in place. The tension applied by the tensioning device is preset or predetermined by the setting of the adjusting nut 55, and, as in the embodiment of Figures 5-7, the stresses on the screening 1 are reduced by the resiliency or yieldability of the arms 60 of the lever 47.

From the above detailed description it will be apparent that there has been provided an improved collapsible window screen which may be applied to any window opening, effectively seals that opening against insects and the like and, due to the presettability of its tensioning device, is enabled to apply uniform tension to the screen on each closing, thereby greatly prolonging the life of the screen. It should be understood that the described and disclosed embodiments are merely exemplary of the invention and that all modifications are intended to be included which do not depart from the spirit of the invention or the scope of the appended claims.

Having described my invention, I claim:

1. In a frameless window screen having spaced rails connected by screening, the combination of a bracket secured to a side of a window frame and having a portion projecting substantially flush with an outer face of said side into a window opening defined thereby, a hook on one of said rails and engageable with said projecting portion of the bracket, a cut-back edge on said one rail beyond said hook, and angularly disposed surfaces on said one rail contiguous to said edge, said one rail on tensioning of said screen rocking about said bracket on said hook for engaging said contiguous surfaces with confronting surfaces of said frame.

2. In a frameless window screen having a rail on one side thereof, a tensioning device for locking said screen to a sill of a window frame comprising a vertically directed screw mounted on said sill and having an elongated head, a latch on said rail and including a lever, and a pair of spaced cam surfaces on said latch, said lever on locking of the device engaging and camming said head on said cam surfaces to locked position.

3. In a frameless window screen having a rail on one side thereof, a tensioning device for locking said screen to a sill of a window frame, comprising a screw on said sill and having an elongated head, a latch on said rail, transversely spaced cams on said latch, a lever on said latch and pivoted between said cams, and means on said latch for locking said lever in locked position, said lever on locking, engaging said head and cooperating with said cams for camming said head to locked position.

4. In a frameless window screen having a rail on one

side thereof, a tensioning device for locking said screen to a sill of a window frame, comprising a screw on said sill and having a transversely elongated head, a latch on said rail, said latch having a longitudinally extendable body portion, transversely spaced ears on said body portion adjacent a lower extremity thereof, a lever pivoted between said ears, and a detent on said body portion above said ears for locking said lever in locked position, said lever on locking of said device engaging and forcing said head onto said ears.

5. In a frameless window screen having a rail on one side thereof, a tensioning device for locking said screen to a sill of a window frame, comprising a headed anchor member on and adjustable vertically of said sill, a latch member having a pair of transversely spaced ears for straddling said anchor member, cam surfaces on said ears and engageable with the head of said anchor member, a U-shaped lever connected to said latch member and pivoted between said ears, said lever having an enlarged head portion passable over said head of said anchor member, and means on said latch member for locking said lever in locked position, said anchor member on insertion of the head thereof through said lever being cammable thereby on said cam surfaces to locked position.

6. In a frameless window screen having a rail member on one side thereof, a tensioning device for locking said screen to a side member of a window frame, comprising catch means on one of said members, and latch means on said other member and including cam means and pivoted lever means, said lever means being engageable with said catch means and operable on engagement therewith to move said catch means into engagement with and along said cam means and pull said rail member

30 on said other member and including cam means and pivoted lever means, said lever means being engageable with said catch means and operable on engagement therewith to move said catch means into engagement with and along said cam means and pull said rail member inwardly and perpendicularly of said frame member toward said catch means.

7. In a frameless window screen having a rail member on one side thereof, a tensioning device for locking said screen to a sill member of a window frame, comprising catch means on one of said members, and latch means on the other of said members and including cam means attached to said other member and lever means pivotally connected to said cam means, said lever means being engageable with said catch means and operable on engagement therewith to move said catch means into engagement with and along said cam means to locked position.
